DESIGN FOR AN ELECTRIC SAFETY SWITCH

Ralph A. Millermaster, Milwaukee, and Clifford Brooks Stevens, Fox Point, Wis., assignors to Cutler-Hammer, Inc., Milwaukee, Wis., a corporation of Delaware

Application January 2, 1941, Serial No. 97,774

Term of patent 14 years

To whom it may concern:

Be it known that we, Ralph A. Millermaster and Clifford Brooks Stevens, citizens of the United States and residents of Milwaukee and Fox Point, respectively, in the county of Milwaukee and State of Wisconsin, have invented a new, original, and ornamental Design for an Electric Safety Switch, of which the following is a specification, reference being had to the accompanying drawing, forming part thereof.

Figure 1 is a front elevational view of an elec-

tric safety switch incorporating our new design.

Figure 2 is a side elevational view of the safety switch shown in Fig. 1, and

Fig. 3 is an end view of the safety switch shown in Figs. 1 and 2.

We claim:

The ornamental design for an electric safety switch, substantially as shown.

RALPH A. MILLERMASTER.
CLIFFORD BROOKS STEVENS.
